UNITED STATES PATENT OFFICE.

ALEXANDER FERDINAND VICTOR, OF TOLEDO, OHIO.

MOVING-PICTURE MACHINE.

976,954.

Specification of Letters Patent. Patented Nov. 29, 1910.

Application filed February 14, 1910. Serial No. 543,749.

To all whom it may concern:

Be it known that I, ALEXANDER FERDINAND VICTOR, a subject of the King of Sweden, residing at Toledo, in the county of Lucas 5 and State of Ohio, have invented new and useful Improvements in Moving-Picture Machines, of which the following is a full, clear, and exact description.

My invention relates to moving picture 10 machines, and particularly to machines capable of either taking pictures of moving objects or projecting such pictures upon a screen with equal facility.

One of the objects of my invention is to 15 provide an invention of this character which is so constructed, that it is capable of performing its functions by means of simple and easily controlled mechanism, the parts of which are of such dimensions and occupy 20 such a limited space that they can be assembled within a comparatively small case or housing, and the whole easily transported by hand from place to place.

Another object is to provide a simple and 25 effective mechanism for rotating the circular-films for manipulating which my improvements are particularly adapted and at the same time moving the axis of said 30 films laterally for the purpose of taking the photographs upon or projecting the same from the film in spiral progression, through the lense-opening.

Another object of my invention is to provide a suitable finder capable of reflecting 35 the objects it is sought to photograph without inversion, which can be moved out of the way when the pictures on the film are being projected.

Still another object of my invention is to 40 hold the portion of the film upon which the picture is being taken or from which the picture is being projected, stationary, during the performance of these functions.

These and other objects I accomplish by 45 the means hereinafter fully described and as particularly pointed out in the claims.

In the drawings:—Figure 1 is a rear elevation of my invention showing the cover opened and a portion of the film holder 50 broken away to expose to view a part of the operative mechanism of the machine. Fig. 2 is a front elevation of a portion of the machine showing the door of the chamber in which film actuating mechanism is contained, open. Fig. 3 is a vertical section 55 taken on dotted line 3, 3, Fig. 1, looking in

the direction indicated by the arrows. Fig. 4 is a vertical section taken on dotted line 4, 4, Fig. 1, looking in the direction indicated by the arrows. Fig. 5 is a horizontal section taken on dotted line 5, 5, Fig. 1. Fig. 6 is a fragmentary view showing the shutter mechanism. Fig. 7 is a section of the film holder. Fig. 8 is a diagrammatical view illustrating the action and operation 65 of the film and the actuating devices used in connection therewith.

Referring to the drawings A represents a suitable case, which is preferably rectangular and has its interior divided into two 70 compartments by a vertical longitudinal partition *a*. The back of the case is preferably hinged to the side thereof opposite that near which the lens is located and is constructed so as to be locked when it is closed. 75 The partition *a* is located so as to provide a practically square compartment, one side of which is bounded by the wall *b* of the case to which the back is hinged, and both the said partition, and the inner surface 80 of this wall *b* are provided with vertical cleats so as to provide grooves in which the vertical edges of a vertically removable film-holder *B* are adapted to slide, when said holder is inserted in place in the said compartment or withdrawn therefrom through 85 a laterally elongated slot in the top of the case. When this film-holder *B* is in its proper position within the case its lower 90 edge rests on the bottom of the case.

The film-holder *B*, just referred to preferably consists of a wooden rectangular slide, the sides of which consist of corresponding wooden plates, *c*, *c*, that are separated a slight distance apart, and have their edges next the bottom, the wall *b* and the top of case, connected by suitable strips of wood or other material. The strip *d* connecting the upper edges of these plates is made of slightly larger dimensions than the strips connecting the other edges thereof, and when the holder is inserted in place the shoulders resulting from increasing the dimensions of this strip *d* will rest upon the marginal edges of the slot in the top of the case and afford a hand-grasp for conveniently inserting and withdrawing the holder. At about its center of height the plates of the film-holder are provided on the inner opposing surfaces thereof with transverse horizontal grooves *e*, *e*, that extend from the open side of the film holder to a point past

the center of width of the same, and are adapted to be engaged by the upper and lower studs e' , e' , of a carrier E , for the circular film F , which latter constitutes the 5 subject-matter of an application for Letters Patent of the United States, filed by me January 28, 1910, No. 540,541. One of the studs of carrier E is extended through the central opening in the film, and when it is desired 10 to move said film laterally to bring it into proper position back of the lens-opening, said carrier is moved laterally by means of a slotted arm G , the upper end of which is secured to a spindle g , that is journaled in 15 suitable bearings in the top strip d of the film-holder. One end of spindle g extends through its bearings and is bent so as to afford a finger-grasp h , which, when the film is wholly within the holder will be parallel 20 with the top of the case, substantially as shown in the drawings.

The partition a of the case is provided with a vertical slot 2, which registers with the opening between the plates at the open 25 side of the film-holder, and between the said partition a and the side-edge of the case, opposite that to which the back is hinged, the compartment is divided into a front and rear section by a vertical partition 3 arranged parallel to the front of the case, just 30 in front of slot 2. This partition 3 is provided, at a short distance from partition a , with an opening 4 through which the pictures are thrown upon the screen or from 35 which they are projected, and when it is desired to move the circular film F the finger-grasp h is moved so as to swing slotted arm G toward the partition a and thereby cause carrier E together with the circular-film F engaged thereby to move 40 through slot 2 until the portion of the film it is desired to expose back of the lens opening 4, is in proper position.

In order to keep the portion of this film 45 back of opening 4, stationary, and prevent any vibration or shifting thereof, it is engaged on either side of said opening by tension-rollers 5. These tension-rollers are journaled in the ends of arms 6, 6, which 50 latter are secured to and project from a rock-shaft 7 that is engaged by a torsional-spring 8 near its bearings, that causes said rollers to normally press against the film. This rock-shaft 7 is journaled in suitable 55 bearings in partition a and in the adjacent side-wall of the case and extends through the latter and has a milled knob or other suitable means attached to its outer end, with which to lock it.

As explained in the pending application 60 for patent for the rotatable film, hereinbefore referred to, the film F is provided with a spirally arranged series of small perforations, 9, and the pictures on these films are arranged between the coils of this spiral.

These perforations 9 are engaged by a pick 10, which latter, preferably, consists of a screw tapped through and adjustable in the adjacent end of a vertical beam 11, located in the front section of the compartment in which the actuating mechanism is placed 70 parallel with the partition a . Near its upper end this beam is engaged by a wrist pin 12 projecting from a small wheel 13 on the adjacent end of a horizontal shaft 14, and the lower end of said beam is slotted 75 and has sliding engagement with a stud 15 projecting laterally from bracket 16, which latter is secured to and projects rearwardly from partition 3. Shaft 14 is journaled in 80 suitable bearings near wheel 13, and also in or near the adjacent side of the case, and is provided with a pinion 17 next said side, that is engaged by a large gear 18 mounted upon the inner end of a spindle that is also 85 journaled in the side of the case and has on its outer end a removable handle 19 with which to turn it. When handle 19 is turned shaft 14 rotates rapidly and the beam 11 reciprocates like a pitman and so that the 90 pick carried by its upper end will pass through a slotted opening 20 in partition 3 and its point will engage during a portion of the cycle of its movement the perforations 9 in the film consecutively and rotate 95 said film and at the same time draw the same laterally toward the lens-opening 4, so as to bring the picture or the surfaces upon which the pictures are to be taken successively back of said opening in their regular progression. This lateral movement of the film is 100 due to the fact that the beam 11 is arranged at a tangent to a circle struck from the center of the film and the point of the pick engages the openings at a point intersected 105 by the horizontal plane intersecting the center of the film, and, when it reciprocates, it moves straight downward from this point and shifts the plate sidewise a distance corresponding to the difference in the radius 110 between the center of the film of the next opening of said series. At the inner end of the spiral series of perforations the film is provided with a segmentally elongated or enlarged opening 21.

Between its bearings shaft 14 has a small mitered pinion 22 mounted thereon, which engages a pinion 23 on the adjacent end of a spindle 25 journaled in a suitable frame 24 and extending horizontally at right angles 120 to shaft 14. The forward end of spindle 25 extends through a sheet metal plate 26 forming the front of the front section of the chamber in which the actuating beam 11 operates, and its forward extremity has a 125 circular shutter 29 secured thereon, consisting of an opaque plate, preferably of gutta percha, which has a segmental slot 27 therein, which as said shutter revolves, alternately opens and closes the opening 28 in said 130

cover from the rear of which an alining tube extends toward partition 3, which is concentric with the opening 28 and with the lens-opening 4.

5 In the front of the case, in alinement with the exposure opening 4 in partition 3 is a screw-threaded opening in which a suitable lens 30 can be removably secured and in the hinged back of the case there is another 10 opening 31 in which the tubular casing 32 of a suitable electric or other lamp 33 is secured, when the machine is used for projecting the pictures from the film to a screen. I also employ a picture finder which consists 15 of a suitable tube 34 the upper end of which extends through the top of the case and is provided with a cap 40 that screws over the same to keep it closed when not in use. This tube depends down into the rear section of 20 the exposure chamber in the vertical plane of the exposure opening 4 in partition 3, and another tube 35 is arranged telescopically over the lower depending end of tube 34 that is adjusted by means of a set-screw 25 36. The lower tube 35 passes through a guide strap 37 secured to and projecting from a cross bar 38, and its lower end is bent toward partition 3, at right angles to its length and in the angle thereof a suitable mirror 39 is placed that reflects the image of the object within the focus of the lens up so that the picture may be seen in the upper end of the tube. The lower tube 30 of this finder is adjustable up out of the way 35 when the machine is in use either taking pictures or projecting the same.

What I claim as new is:—

1. A moving picture machine comprising a film-holder having bearings for the axial 40 elements of the film and means for moving the said axial elements in and out of said film holder.

2. A moving picture machine comprising a film-holder having immovable opaque 45 sides, bearings for the axial member of the film, and means for moving said axial members in and out of said holder.

3. A moving picture machine comprising a film-holder having immovable sides, laterally elongated bearings for the axial member of the film, and means for moving said axial members in and out of said holder.

4. A moving picture machine comprising a film-holder having immovable sides and 55 laterally elongated bearings for the axial member of said film, and a carrier having journaling members which are adapted to be seated and move laterally in said bearings.

5. A moving picture machine comprising 60 a film-holder having immovable sides, laterally elongated bearings for the axial elements of the film, and an arm pivoted in the edge of said holder and adapted to engage the axial element of the film and move the 65 same laterally in said bearings.

6. A moving picture machine comprising a film-holder having immovable sides, laterally elongated bearings for the axial elements of the film, a carrier having journaling members adapted to engage said bearings, and an arm pivoted in the edge of said holder, and adapted to engage one of said members of the carrier of the film and move the same laterally in said bearings. 70

7. A moving picture machine comprising a film-holder having immovable bearings therein, a carrier having journaling studs adapted to engage said bearings and center the film, and an arm pivoted at one end in the edge of said holder and having an elongated slot in its opposite end and adapted to engage said carrier and move it laterally. 75

8. A moving picture machine comprising a suitable case, a film holder bodily removable from said case and having bearings for 80 a rotatable film that extend from the center to the open edge of said holder. 85

9. A moving picture machine comprising a film-holder having bearings for a rotatable film, and devices exterior to said holder that directly engage said film and impart an intermittent rotative movement thereto. 90

10. A moving picture machine comprising a film holder having suitable bearings for a rotatable film, and devices exterior to said holder that directly engage said film and simultaneously impart an intermittent rotative and sidewise movement thereto. 95

11. A moving picture machine comprising a film-holder provided with suitable bearings for a rotatable film having a curved series of perforations therein, of a pick adapted to engage said perforations, and impart an intermittent rotative movement to said film. 100

12. A moving picture machine comprising means for journaling the axial elements of a rotatable film contained therein, a pick operating in a plane tangential to the center of the film and adapted to engage perforations in said film. 110

13. A moving picture machine comprising a case having a film compartment and an exposure compartment separated therefrom by a partition having a slit extending transversely therein through which said film is adapted to move and means in said exposure compartment for rotating said film. 115

14. A moving picture machine comprising a case having a film-holder compartment, 120 and an exposure compartment separated therefrom by a partition having a slit extending transversely therein, a film holder removably retained in said film compartment and having the side next thereto open, 125 and communicable with said slit, and means in said exposure compartment for rotating said film.

15. A moving picture machine comprising a case having a film-holder compartment, 130

and an exposure compartment separated therefrom by a partition having a slit extending transversely therein, a film-holder removably retained in said film compartment and having the side next thereto open, and communicable with said slit, and means in said exposure compartment for rotating and moving said film sidewise.

16. A moving picture machine comprising a case having a film compartment and an exposure compartment separated therefrom by a partition having a slit extending transversely therein through which said film is adapted to move, a pick adapted to engage 10 the perforations in said film and rotate the same.

17. A moving picture machine comprising means for centering a rotatable film, a reciprocal bar movable in a plane tangential 20 to the center of said film, and a pick carried in the end thereof, and adapted to engage perforations in said film.

18. A moving picture machine comprising means for centering a rotatable film, a reciprocal bar movable in a plane tangential to the center of said film, and an adjustable pick carried in the end thereof and adapted 25 to engage perforations in said film.

19. A moving picture machine comprising means for centering a rotatable film, a reciprocal bar movable in a plane tangential to the center of said film, a pick carried 30 in the end thereof and adapted to engage perforations in said film, a wheel having a wrist-pin engaging said bar, a shaft on the end of which said wheel is secured and means for revolving the same.

20. A moving picture machine comprising a case having a film compartment and an exposure compartment separated therefrom 40 by a partition having a slit extending transversely therethrough, a partition dividing the exposure compartment into a front and rear section having an exposure opening 45 therein means for pressing the exposed portion of the film back of said opening and

mechanism for rotating the film back of said opening.

21. A moving picture machine comprising a case having a film compartment and an exposure compartment separated therefrom by a partition having a slit extending transversely therethrough, a partition dividing the exposure compartment into a front and rear section having an exposure opening 50 55 therein, spring actuated means for pressing the exposed portion of the film back of said opening and mechanism for rotating the film back of said opening.

22. A moving picture machine comprising a case having a film compartment and an exposure compartment separated therefrom by a partition having a slit extending transversely therethrough, a partition dividing the exposure compartment into a front and rear section having an exposure opening 60 65 therein, means consisting of a rock-shaft, a torsional spring engaging the same, and arms projecting from said rock-shaft for pressing the exposed portion of the film 70 back of said opening and mechanism for rotating the film back of said opening.

23. A moving picture machine comprising a case having a film compartment and an exposure compartment separated therefrom 75 by a partition having a slit extending transversely therethrough, a partition dividing the exposure compartment into a front and rear section having an exposure opening 80 therein, a rotatable pick adapted to move through a suitable opening in said last mentioned partition, and engage and rotate the film on the other side thereof, and a pressure member for pressing the exposed portions of the film back of the exposure opening. 85

In witness whereof I have hereunto set my hand this ninth day of February 1910.

ALEXANDER FERDINAND VICTOR.
